UNITED STATES PATENT OFFICE.

LESTER W. COLLINS, OF ST. PAUL, MINNESOTA.

REFRIGERATOR CAR.

1,421,913.

Specification of Letters Patent.

Patented July 4, 1922.

Application filed October 7, 1919. Serial No. 328,980.

To all whom it may concern:

Be it known that I, LESTER W. COLLINS, a citizen of the United States, residing at St. Paul, in the county of Ramsey and State 5 of Minnesota, have invented new and useful Improvements in Refrigerator Cars, of which the following is a specification.

This invention relates to improvements in refrigerator cars or cooling rooms. Its primary object is to provide improvements in 10 overhead refrigerator bunkers. In this invention an overhead ice basket or baskets are employed allowing the air in the car to come more freely into direct contact with a 15 greater area of refrigerant than heretofore thereby producing lower and more even temperature than in prior art devices.

This invention provides an ice basket or baskets located in the upper portion of a 20 refrigerator car, cooling room or other refrigerating provision chamber, near which is arranged a combined drip pan and air baffle, said basket being supported above the drip pan and air baffle so that air is 25 caused to circulate completely around the pieces of ice contained in the basket and to follow a definite course of circulation, whereby the lading enclosed in the refrigerating car or chamber is cooled in a minimum 30 time and maintained at a minimum temperature. This invention also provides suitable means for the ready removal of the combined drip pan and air baffle and the ice basket for repairing. This invention also 35 comprises features of construction and combination of parts hereinafter more particularly described and claimed.

In the accompanying drawings forming 40 part of this specification, Fig. 1 is an elevation in longitudinal central section through a portion of a refrigerator car showing my invention applied thereto; Fig. 2 is a longitudinal section taken on the line 2—2 of Fig. 1; Fig. 3 is a cross section of a detail, on an enlarged scale, taken on the line 45 3—3 of Fig. 1; Fig. 4 is a plan of the combined drip pans and air baffles in assembled position when removed from the car; Fig. 5 is a section of a detail taken on the 50 line 5—5 of Fig. 4; Fig. 6 is a section of a detail taken on the line 6—6 of Fig. 4; Fig. 7 is a section of a detail taken on the line 55 7—7 of Fig. 4; Fig. 8 is a section of a detail taken on the line 8—8 of Fig. 4; and Fig. 9 is a section of a detail taken on the line 9—9 of Fig. 4.

In the drawings let A indicate the body of a refrigerator car having the usual floor 10, sides 11 and 12, ends such as 13 and roof 14, all of which are thoroughly insulated according to general practice in constructing refrigerator cars or storage houses. The roof of the car has the customary ceiling 16 which is cut away at its central portion in order to raise the ice basket elements which are employed as near the roof of the car as possible to give ample head room below the drip pans. As shown three ice baskets are provided indicated by B, C, and D, although it will be understood that my invention contemplates the use of one or any number of ice baskets within the spirit thereof. Each of these ice baskets (see Fig. 3) is of rectangular shape, made out of woven wire with the top open, whereby air is free to circulate through the floor and side walls and around the ice therein. These ice baskets are arranged in series longitudinally and supported by means of a skeleton cradle E, said cradle in turn being supported by a pair of angle elements 17 and 18 which are fastened longitudinally to the side walls 11 and 12 of the car by means of bolts 19 or other suitable fastening means passing through the walls, car framing and said angle members. Upon the lower inwardly extending flange members of these angle elements are suitably supported other angle irons 21 and T irons 22, there being a set of angle irons and T irons for each basket, the angle irons being arranged so that the bottom corners of the basket at all 4 sides rest therein. The transverse or end angle iron members at the lower corners of the baskets extend beyond the sides of the ice basket and are adapted to rest upon the angle members 17 and 18. The longitudinal angle members at the lower corners of the basket rest upon and are secured to the transverse angle members, the securing means being by bolts 23 or other suitable detachable means. The T members 21 extend transversely below and support the longitudinal angle members the ends of said T members also resting upon the longitudinal angle members 17 and 18. The ends of the transverse angle members and T members are detachably secured to the longitudinal angle members 17 and 18 by bolts 24 or other suitable means. By loosening the bolts 23 and 24 the ice basket supports or cradles can be easily removed and the baskets low-

ered for making repairs when desired. Filler blocks 25 are placed upon the upper sides of the T members so as to provide even support for the bottom of the ice basket to 5 prevent sagging. As many T members are provided across the car below the baskets as is necessary to assist the end transverse angle members in amply supporting the ice baskets to prevent any sagging and to prevent 10 all side and end thrust. The construction described for supporting the ice baskets has a maximum strength and minimum weight of material without obstructing the free circulation of air around the ice in the 15 ice baskets which is advantageous. The roof of the car is provided with suitable hatchways, there being a pair 26 for each basket located at each side of the running board 27. Each of these hatchways is closed in 20 the usual manner such as by a plug 28 and a hinged cover 29. The lower ends of the passages in the hatchways are flared outwardly and downwardly at 30 so as to give clearance and thus facilitate the filling of 25 the baskets with ice or with a mixture of ice and salt or other chemicals. The ice baskets are spaced a short distance from each other and from the sides of the car which facilitates their removal or replacement 30 from below and allows more perfect circulation of the air through the baskets thus producing maximum contact with the refrigerant.

The combined drip pan and air baffle is 35 composed as illustrated of six sections, F, G, H, I, J and K, there being a pair of sections arranged transversely below each ice basket, the sections of each pair being spaced apart. These sections are supported on the side 40 walls of the car by longitudinally disposed blocks 31 which are removably secured by means of bolts 32 or other suitable means, passing through the blocks, walls and framing of the car. The combined pan and baffle 45 sections are arranged in two series there being three adjacent sections on each side of the car, the endmost sections being secured against longitudinal movement by end blocks 33, which may be separate elements or when 50 desired continuations of the side supports 31. The sections F, G, H, I, J and K slant downwardly from near the longitudinal center line of the car towards the side walls so as to provide drainage. The inner ends to 55 ward the longitudinal center line of the car of said sections which are spaced a short distance apart, provide a central longitudinal air duct 35 through which air passes freely from over and around the ice in the ice 60 basket elements, downwardly into the provision chamber, in the car or room being cooled. Said upper and inner ends are held spaced apart by spacing blocks 36 and said ends are removably hung from the ice basket 65 cradles by means of bolts 37 or other suitable

means. It will be observed the ice basket cradles which support the ice baskets and the combined drain trays and baffles are entirely supported by the side walls of the car. Thus the roof is free from the load of the refrigerating means. 70

The surrounding edges of each combined tray and air baffle slant upwardly and outwardly to provide dams 38 which prevent any water dripping from the ice from passing into the provision chamber. The combined drip pans and air baffles are surfaced with thin sheet metal plates 39 to prevent water leaking through the pans. The inclined surfaces of the dams also prevent the 80 metal from cracking where it is bent up thus reducing to a minimum tendency to leak. The ends of the endmost trays facing the ends of the car are provided with air baffle walls 40, which terminate a short distance below the ceiling or roof of the car so that air from the lading chamber passes upwardly over the baffles, circulating in and around the ice in the ice baskets and then back again into the lading chamber through 90 the air ducts 35. Cover plates 41 over the air ducts 35 sufficiently protect against any water dripping from the ice through the ducts 35 and into the provision chamber. The lower ends of the combined pans and 95 air baffles adjacent to the side walls of the car are provided with suitable drain ducts 42 leading downwardly through the side walls and out from the car. The lining plates 39 extend upwardly over the baffle or rear walls 100 40. This protects against water splashing from the pans or ice in the baskets into the provision chamber. The car body may when desired be provided with floor racks 43, end air circulating ducts 44 and up and down 105 spacing strips 45 on the side walls, all of which permit air to circulate freely through and around the lading.

In operation after the ice baskets have been filled with refrigerant such as ice or a mixture of ice and salt or other chemicals and the hatchways closed, air circulates freely around all sides of the basket and the refrigerant contained therein, thus being lowered in temperature to a minimum. The 110 cold air which has come into intimate contact with the refrigerant passes downward through the ducts 35 into the lading chamber, forcing the return of the air in the provision chamber over the end baffles 40 to the 115 ice in the ice baskets. Thus a well defined circulation of cooling medium occurs throughout the provision chamber, the current of air passing downwardly near the center of the car and towards both ends and thence rising and returning in the upper portion and towards the center. 120

In accordance with the patent statutes I have described the principles of operation of my invention together with the appa- 125 130

ratus which I now consider to represent the best embodiment thereof, but I desire to have it understood that the construction shown is only illustrative and that the invention can 5 be carried out by other means and applied to uses other than those above set forth within the scope of the following claims.

Having described my invention, what I claim as new and desire to protect by Letters 10 Patent is:—

1. A body structure containing a provision chamber, a plurality of assembled ice baskets of open work structure distanced apart and situated near the top and away from ends 15 of said structure, skeleton cradle elements secured to the side walls of said structure for supporting said baskets in position and a plurality of assembled combined drip pan and air baffle elements secured to said side 20 walls and spaced from said ice basket elements for conducting the drip away from the ice in the basket elements and permitting air to circulate freely from the provision chamber over, through, below and around 25 the ice in the basket elements.

2. In combination with a body structure of greater length than width, an overhead ice basket remote from the ends and spaced from the sides in said structure, a skeleton 30 cradle secured to said body structure for supporting said basket, a drip pan supported below said basket having a down draft duct, and an air baffle at the outer portion of said pan 35 away from said basket, said pan and baffle being arranged so as to assist in directing air from in said body structure up, through and around the basket, around the refrigerant and below the basket and thence down through said duct 40 and below the pan.

3. A body structure containing a provision

chamber, a plurality of ice baskets of open work structure distanced apart near the top and away from the ends of said structure, skeleton cradle elements for supporting said 45 baskets in position and a plurality of drip pans supported below and away from said ice basket elements for conducting the drip away from the ice in the basket elements and permitting air to circulate freely from 50 the provision chamber over, through, below and around the ice in the basket elements.

4. A body structure containing a provision chamber, a plurality of assembled ice baskets of open work structure, situated and supported near the top and away from the ends of said structure, and a plurality of assembled drip pan and air baffle elements spaced from and below said basket elements for conducting the drip away from the ice in 60 the basket elements and permitting air to circulate freely from the provision chamber over, through, below and around the ice in the basket elements.

5. In combination with a body structure, 65 an overhead ice basket spaced from the side walls of said structure, a skeleton cradle secured to said body structure for supporting said basket, a drip pan supported below said basket having a down draft duct, and an 70 air baffle at the outer portion of said pan away from said basket, said pan and baffle being arranged so as to assist in directing air from in said body structure up, through and around the basket, around the refrigerant and below the basket and thence down through said duct and below the pan.

Signed at St. Paul, in the county of Ramsey and State of Minnesota, this 22nd day of September, 1919.

LESTER W. COLLINS.
